PROCESS FOR THE TREATMENT OF
OIL-WAX MIXTURESJoseph A. Alexander, Philadelphia, Pa., assignor
to The Atlantic Refining Company, Philadelphia, Pa., a corporation of Pennsylvania

Application January 30, 1935, Serial No. 4,158

5 Claims. (Cl. 196—20)

The present invention relates to an improved process for the separation of hydrocarbon oil-wax mixtures and relates particularly to an improvement in the process disclosed in a co-pending application of S. W. Ferris, Serial No. 4,157, filed January 30, 1935.

Briefly, the process disclosed in the co-pending application of Ferris consists in preparing an oil-wax mixture, for example, by distillation, which upon cooling to the desired separating temperature will crystallize wax to the extent of 10% or less of the total volume of the mixture; or the dilution of a wax-bearing stock with a suitable solvent, so that upon cooling to the desired separating temperature, wax will crystallize to the extent of 10% or less of the total volume of the mixture. The oil-wax mixture so prepared is then cooled to the desired temperature, with or without agitation, in such a manner as to effect a dispersion of the wax crystals throughout the mother liquor with reasonable uniformity. If agitation is resorted to, the cooled mother liquor containing the wax crystals is thereafter permitted to stand, unagitated, for sufficient time to effect the formation of a highly porous wax mass, the structure of which has a certain degree of mechanical strength, such mass containing less than substantially 10% of solid wax per unit volume of the mass. The displacement of the mother liquor from the cooled wax mass is then accomplished by passing a displacing liquid, preferably an oil solvent, through the mass in such a manner that a substantially horizontal interface is maintained between the mother liquor in the mass and the displacing liquid, the displacement pressure (differential pressure or pressure drop through the wax mass) being of the order of 5 lbs./sq. in. or less, per foot depth of wax mass, and the concentration of crystalline wax being less than substantially 20% by volume of the mass in which mother liquor is still present. The displacement step is usually accompanied by the settling or compacting of the wax mass from which the mother liquor is being removed, but such compacting is controlled to prevent the concentration of crystalline wax in the mass from exceeding substantially 20% by volume of the mass. This control is obtained by the proper adjustment of the quantity of wax crystallized from the mother liquor to form the initial wax mass, the rate and degree of cooling, the differential pressure required for displacement and the gravity differentials between wax, mother liquor and displacing liquid. Upon completion of the displacement operation the solvents employed may be separated from the oil and wax fractions by distillation.

In carrying out the process, it is necessary to control the quantity of wax in the mother liquor so that the crystalline wax content of the mass

resulting from the chilling of the mother liquor will not exceed substantially 10% of any unit volume of the mass at the beginning of the displacement operation. In most instances, it has been found that the crystalline wax contained in the wax mass at the beginning of the displacement step should be of the order of from 1% to 6% by volume, and preferably of the order of from 2.5% to 4.5% by volume; it may, however, be as high as 10% by volume depending upon the character of the wax crystals. Furthermore, in general, the differential pressure required in effecting displacement does not exceed substantially 5 lbs./sq. in. per unit (1 foot) depth of the wax mass, and usually at the outset does not exceed 2 lbs./sq. in. It is to be understood, however, that at some stage of the operation, and particularly during the latter part thereof, the pressure may be somewhat in excess of 5 lbs./sq. in. per 1 foot depth of the mass.

In the displacement process as above outlined, it has been customary to employ a vertical, straight-walled cylindrical vessel for carrying out the displacement of mother liquor from the crystalline wax mass, such vessel being provided with heating and/or cooling means, feed and discharge connections and a screening means at the top or bottom of the vessel to prevent the escape of wax crystals, the position of such screening means depending upon the direction of flow, i. e., upward or downward displacement.

It has been found, in some instances, that during the displacement of mother liquor from the wax mass contained in the aforementioned straight-walled vessels, cracks or channels will appear in the mass or the mass will contract from the walls of the vessel leaving an annular channel thru which washing liquid is prone to flow, thus rendering the displacement and washing operation very inefficient. The formation of cracks or channels is highly undesirable, inasmuch as the displacing or washing liquid will tend to flow thru the paths of least resistance, i. e., the cracks or channels, with the result that considerable quantities of mother liquor will remain in those portions of the wax mass thus bypassed.

I have discovered that such difficulties may be obviated to a great extent by employing a vessel having sloped or tapered walls, preferably a jacketed vessel of truncated conical shape. During the step of displacing the mother liquor from the wax contained in such a tapered vessel, that portion of the mass in which the mother liquor has been replaced by displacing liquid tends to settle or compact in a vertical direction and simultaneously in a horizontal direction due to the progressively decreasing diameter of the vessel. The horizontal compacting thus obtained prevents the formation of cracks or channels during

displacement and permits a more uniform and efficient removal of mother liquor from the wax mass.

For purposes of illustration, reference is made 5 to the accompanying drawings in which Fig. 1 represents diagrammatically, apparatus suitable for carrying on my process; and Figs. 2, 3, and 4 represent modifications of my displacement vessel.

10 Referring to Fig. 1:

From a steam jacketed stock tank 1, 40 parts, for example, of a wax-bearing distillate from East Texas crude oil having a pour test of 125° F., and a Saybolt universal viscosity of 60 seconds at 210° F., is withdrawn through valve-controlled pipe 2 and pumped by pump 3 through valve-controlled pipe 4 into mixing tank 5 provided with heating coil 6 and stirrer 7. Simultaneously or subsequently 60 parts, for 15 example, of ethylene dichloride is withdrawn from solvent tank 8 by means of valve-controlled pipe 9 and pumped by pump 10 through valve-controlled pipe 4 into mixing tank 5. Herein the solvent and distillate containing wax 20 is agitated at a temperature of, for example, 120° F., until a homogeneous solution is obtained. The resulting solution is passed from the mixing tank 5 by means of valve-controlled pipe 11 and is pumped by pump 12 thru valve-controlled pipe 13 to chilling device 14, wherein 25 the solution is cooled until the temperature is of the order of, for example, 85° F., and a portion of the wax has crystallized. This oil-wax-solvent mixture is passed from the chilling device 14 through valve-controlled pipe 15 into the brine-jacketed displacement tower 16 above the screen 17. Prior to the introduction of the chilled mixture into the tower 16, air pressure is applied to brine tank 18 through valve-controlled pipe 19 provided with valved vent 19a, and brine is forced through valve-controlled pipe 20 and pipe 21 into the conical lower section of tower 16 until it barely covers the screen 17. The brine and screen 17 thus support the 30 chilled oil-wax-solvent mixture in the tower 16. The mixture contained in the displacement tower 16 is then cooled at a rate of, for example, from 1° F. to 4° F. per hour, until the temperature of the mixture is of the order of, for 35 example, 65° F., and the desired final quantity of wax has crystallized out. The cooling in the tower 16 may be effected by circulation of cold brine in the tower jacket and/or by the employment of brine coils or pipes (not shown) installed within the tower.

The mixture is preferably allowed to remain in a quiescent state within tower 16 during the final cooling period, in which time the wax crystals form an agglomerate mass of appreciable mechanical strength while still retaining a high degree of free space or porosity thruout which the mother liquor is distributed. At the completion of the cooling period, 100 parts of a displacing liquid, for example, naphtha of 50° A. P. I. gravity, is passed from the displacement liquid tank 22 through valve-controlled pipe 23, cooled to about 65° F. in cooling coil 24 and introduced into the displacement tower 16 by means of valve-controlled pipe 25, above the 60 surface of the chilled oil-wax-solvent mixture contained therein. The displacing liquid is introduced in such a manner as to prevent substantial disturbance of the wax mass from which the oil and solvent are to be displaced. Preferably simultaneously with the introduction of

the displacing liquid at the top of tower 16, brine is withdrawn from the bottom of said tower and returned to the brine tank 18 by means of valve-controlled pipe 26. Oil and solvent from the wax mass, displaced downwardly 5 by the incoming displacing liquid, is withdrawn from the bottom of tower 16 and passed through valve-controlled pipes 27 and 28 into receiving or heavy efflux tank 29. If necessary, slight pressure may be applied to the tower 16, above 10 the level of its contents, by means of valve-controlled air line 30 provided with valved vent 31. The differential or displacement pressure should preferably be maintained at less than 15 5 lbs./sq. in. per 1 foot depth of the wax mass, in order to prevent undue compacting of the wax crystals. When substantially all of the oil and solvent (heavy efflux) has been displaced from the wax mass into receiving tank 29, as evidenced by a marked change in gravity or 20 other critical property of the liquid issuing from the tower 16, the liquid thereafter withdrawn from the tower is diverted into receiving or light efflux tank 31 by closing valve-controlled pipe 27 and opening valve-controlled pipe 32. 25 This light efflux will consist primarily of displacing liquid containing residual oil and solvent which has been washed from the wax mass. The displacing or washing operation is preferably continued until the effluent from tower 16 30 is principally displacing liquid.

At the completion of the displacing or washing operation, the wax mass containing residual displacing liquid is forced upwardly and out of tower 16 through valve-controlled pipe 33 into 35 wax receiving tank 34, by means of brine introduced into the bottom of the tower from brine tank 18. If necessary, the wax mass contained in tower 16 may be rendered more fluid by the application of steam in the jacket surrounding said tower. The heavy efflux (oil and solvent) in tank 29, the light efflux (oil, solvent and displacing liquid) in tank 31, and the wax containing residual displacing liquid may be withdrawn from their respective receiving tanks 40 by means of valve-controlled pipes 35, 36 and 37 and passed to distilling apparatus (not shown), wherein the solvent, i. e., ethylene dichloride, and the displacing liquid, i. e., naphtha, may be separated and recovered from the 45 oil and wax.

While, in the above instances, I have described the chilling of the solution of oil stock and solvent from the mixing tank 5 as being effected partially within the chiller 14 and partially 55 within the displacement tower 16, I may, if desired, pass the solution directly to the tower by means of valve-controlled by-pass 38 and effect such chilling entirely within the tower 16, or I may chill the solution entirely in the chiller 14 60 prior to the introduction thereof into the displacement tower 16. The latter method of operation may be carried out by pumping the heated solution directly from mixing vessel 5 through valve-controlled pipe 13, chiller 14 and 65 valve-controlled pipe 15 into tower 16. In this instance, the chilled mixture is preferably allowed to remain in a quiescent state within tower 16 for a period of, for example, 4 hours, during which time the crystals form an agglomerate mass having appreciable mechanical strength while still retaining a high degree of free space thruout which the mother liquor is distributed. Due to the gravity differential between the wax and mother liquor a certain 70 75

amount of upward settling of the former occurs, so that at the end of the quiescent period a lower layer of relatively wax-free oil solution is present which may be about 30% of the volume of the total charge. This layer is drawn off from the bottom, at the same time the wax mass settles until upon completion of the removal of the wax-free solution the bottom of the wax mass rests upon the screen. The displacement step is then carried on as above described.

In place of the fully tapered vessel for downward displacement, shown in connection with the above description, I may utilize the partially tapered vessel illustrated by Fig. 2. The vessel (a) is surrounded with a heating or cooling jacket (b) and provided with a displacing liquid inlet pipe (c), a stock charging inlet pipe (d), a screen (f) and a brine inlet and outlet pipe (g) which is also employed as an outlet for mother liquor and displacing liquid.

The displacement vessels represented by Figs. 3 and 4 are suitable for upward, and upward or downward displacement, respectively.

In Fig. 3 the vessel (a') is surrounded with a heating or cooling jacket (b') and provided with a displacing liquid inlet pipe (c'), a stock charging inlet pipe (d'), a screen (f'), a brine inlet and outlet pipe (g') and an outlet pipe (h') for mother liquor and displacing liquid.

In Fig. 4 the vessel (a'') is surrounded with a heating or cooling jacket (b'') and provided with screens (f''). If such vessel is employed in downward displacement, stock is charged thru pipe (d''), brine is introduced or withdrawn thru pipe (g''), mother liquor and displacing liquid are withdrawn thru the same, and displacing liquid is introduced thru pipe (c''). If the same vessel is employed in upward displacement, stock is charged thru pipe (d''), brine is introduced or withdrawn thru pipe (g''), mother liquor and displacing liquid are withdrawn thru pipe (c'') and displacing liquid is introduced thru pipe (i''). In all cases, the final washed wax may be withdrawn from either the top or bottom of the vessel by means of the pipes shown. Furthermore, additional heating or cooling means, such as vertical pipes or coils (not shown) may be installed within the displacing vessels to aid in maintaining the desired temperature therein.

In the description of my process given hereinabove, I have shown that ethylene dichloride may be employed as the crystallizing solvent and naphtha as the displacing liquid. In addition thereto, I may also employ the conventional waxing solvents such as acetone, acetone-benzol, alcohols, esters, ethers, halogenated hydrocarbons and liquefied normally gaseous hydrocarbons.

For brevity, in the appended claims, the terms "solvent liquid" and "displacing liquid" are to be understood to comprehend those compounds in which oil is readily miscible and wax is relatively immiscible at the temperatures employed in the separation of the oil and wax. Also, the term "wax mass" as employed herein and in the appended claims comprehends a porous mass or body of wax crystals containing oil or oil and solvent distributed therethrough.

What I claim is:

1. The process of separating a hydrocarbon oil-wax mixture into oil and wax fractions containing less wax and oil respectively than said mixture,

which comprises producing a wax-containing mixture, cooling said mixture to effect crystallization of wax therefrom and to cause the formation, in a displacement zone of a diameter decreasing in the direction of displacement flow, of a wax mass containing less than substantially 10% by volume of crystalline wax and displacing from said wax mass, without substantial agitation thereof and under a relatively low differential pressure, the liquid constituents of said mass with a displacing liquid.

2. The process of separating a hydrocarbon oil-wax mixture into oil and wax fractions containing less wax and oil respectively than said mixture, which comprises producing a wax-containing mixture, cooling said mixture to effect crystallization of wax therefrom in an amount less than about 10% by volume of said mixture, passing the cooled mixture into a displacing zone of a diameter decreasing in the direction of displacement flow, and displacing from said cooled mixture, without substantial agitation thereof and under a relatively low differential pressure, the liquid constituents of said mixture with a displacing liquid.

3. The process of separating a hydrocarbon oil-wax mixture into oil and wax fractions containing less wax and oil respectively than said mixture, which comprises producing a wax-containing mixture, partially cooling said mixture to crystallize therefrom a portion of the wax, passing the cooled mixture into a displacing zone of a diameter decreasing in the direction of displacement flow, further cooling the mixture to form a wax mass containing less than substantially 10% by volume of crystalline wax and displacing from said wax mass, without substantial agitation thereof and under a relatively low differential pressure, the liquid constituents of said mass with a displacing liquid.

4. The process of separating a hydrocarbon oil-wax mixture into oil and wax fractions containing less wax and oil respectively than said mixture, which comprises diluting said mixture with a solvent liquid, cooling said diluted mixture to effect crystallization of wax therefrom and to cause the formation, in a displacement zone of a diameter decreasing in the direction of displacement flow, of a wax mass containing less than substantially 10% by volume of crystalline wax and displacing from said wax mass, without substantial agitation thereof and under a relatively low differential pressure, the liquid constituents of said mass with a displacing liquid.

5. The process of separating a hydrocarbon oil-wax mixture into oil and wax fractions containing less wax and oil respectively than said mixture, which comprises adding to said mixture a solvent liquid, heating such admixture to a temperature sufficient to effect solution, cooling the solution to effect crystallization of wax therefrom and to cause the formation, in a displacement zone of a diameter decreasing in the direction of displacement flow, of a wax mass containing less than substantially 10% by volume of crystalline wax and displacing from said wax mass, without substantial agitation thereof and under a relatively low differential pressure, the liquid constituents of said mass with a displacing liquid.

JOSEPH A. ALEXANDER.
